UNITED STATES PATENT OFFICE.

BENJAMIN F. OREWILER, OF CHICAGO, ILLINOIS.

BUCKLE.

1,365,721.

Specification of Letters Patent. Patented Jan. 18, 1921.

Application filed May 12, 1919. Serial No. 296,471.

To all whom it may concern:

Be it known that I, BENJAMIN F. OREWILER, a citizen of the United States, residing at Chicago, in the county of Cook and State of Illinois, have invented certain new and useful Improvements in Buckles, of which the following is a specification.

The invention relates to improvements in buckles and has especial reference to apparel buckles for corsets, garters, suspenders and the like.

One of the objects of the invention is to provide a buckle structure which will cleave to the fabric, in adjusted position, and which will not creep or "walk down the web," as a result of application of abnormal strain and subsequent release of the web, as common in so many buckles of this type.

Another object of the invention is to improve the structure to the end that the buckle may be unusually thin, not much thicker than the three thicknesses of the webbing to which it is shown to be attached and which is not deflected to bring the one reach of the fabric in the same vertical plane with another reach thereof.

Another object is to provide a buckle that will, with equal efficiency, coöperate with thick and thin webbing without requiring change of buckle structure, and another object is to generally improve buckle structures, to cheapen the cost of construction and to reduce the number of required parts to ultimate simplicity.

Other, further and more specific objects of the invention will become readily apparent, to persons skilled in the art, from a consideration of the following description when taken in conjunction with the drawings, wherein:—

Figure 1 is an elevation of a buckle attached to a piece of fabric, or webbing.

Fig. 2 is a section taken on line 2—2 of Fig. 1, showing the buckle closed.

Fig. 3 is a similar section showing the buckle open.

Fig. 4 shows the two parts, the frame and the clamping lever, of which the buckle is composed.

Fig. 5 is an enlarged section, similar to Fig. 2, showing more clearly the parts as they appear when the buckle is closed.

In all the views the same reference characters are employed to indicate similar parts.

The buckle is composed, preferably, of two parts, made of sheet metal, comprising, in

general, a frame A and a web clamping member B hinged thereto.

The frame A consists of a back bar 6 in vertical alinement with a pintle bar 7 formed integrally therewith. A front bar 8, also formed integrally with back bar 6, is bent forwardly into a plane substantially parallel with the back bar 6 and on its web engaging edge, it is provided with a series of teeth 9. These teeth, it will be observed, are located in a plane higher than the edge of the back bar, and they coöperate with the interdental spaces between the teeth of the lever B, to permit the same to pass beyond the front bar, to which reference will be hereafter more specifically made. The clamping member B is provided with a part 10, which I shall call a lever and a part 11, which I shall call the locking member and along the edge of the locking member 11, are teeth 12. At the ends of clamping member B are wings 13 to be formed into sleeves that are to surround the pintle bar 7, thereby providing a means by which the member B is pivoted to the member A. The wings 13 are bent around the bar 7, shown in Fig. 5, so that the reach 14 of the fabric is farther removed to the rear of the buckle, when the buckle is open, than it is when the buckle is closed, as clearly shown by the dotted line 15, extending between Figs. 2 and 3. It will therefore be seen that closing the buckle does not deflect the fabric rearwardly of the buckle, but to the contrary permits the fabric to move to a position nearer the front of the buckle. In Fig. 2, where the buckle is closed, the reach 14 is more nearly in vertical alinement with the rear reach 16, than it is, as shown in Fig. 3, when the buckle is open. Consequently when reach 14 moves into line with reach 16 reach 16 is moved forwardly instead of rearwardly into such a position by the act of closing the buckle.

When the lever 10 is depressed so that the parts assume the position shown in Fig. 5, the locking member 11 will pass to the rear of the back bar 6, and, temporarily, by that means, it will compress the webbing, but as it passes over the edge of the back bar 6, it releases the webbing, because, then it has brought the teeth 12 into contact with the webbing and the webbing is displaced by this act forwardly and not rearwardly, whereupon reach 14 and reach 16 are brought into vertical alinement without deflecting the buckle.

Comparing Fig. 2 with Fig. 3, it will be noticed that when the members 11 and 12 are moved to their closed position, more clearly shown in Fig. 5, the webbing is not deflected thereby over the edges of the members 6 and 8, because it is already over the edges of these members, but it is deflected toward their edges and permitted to move forwardly in the act of closing the buckle.

10 When the locking member 11 of the lever is moved to the position shown in Fig. 5, the teeth are brought into position to register with the interdental spaces between the teeth 9 of the frame A, to pass therebetween, but the teeth 12 will pass beyond the teeth 9 when the buckle is closed, and, therefore, the webbing is not forced between the teeth 9 and 12 for the purpose of holding it but reaches 17 engages the teeth 9 and reaches 20 14 engages the teeth 12 and an effort to straighten out these parts of the fabric tends to cause the teeth to more intimately engage the fabric and hold it positively against movement.

25 It will be observed that the locking member 11 and the teeth 12 are substantially parallel with the buckle lever 10 and not at right angles thereto, as common in buckles of this type.

30 To open the buckle, to release the webbing, it is necessary to move the lever 10 forwardly, holding the frame or finger piece A in position, during this action, and to move the locking member 11 out of the slot 35 18 in the frame A, or until the locking member 11 has passed the vertical plane in which the teeth 9 are located.

It will be noticed that the locking member 11 is slightly curved rearwardly and 40 that the teeth 12, while they are not in the same plane as the locking member, being in front of the locking member when the buckle is closed, as clearly shown in Fig. 5, are also curved, so as to cause the points of 45 the teeth to be presented to better advantage to the fabric with which they are in contact.

Any stress applied between the reaches 50 16 and 17 and reach 14, tends to straighten the fabric and thereby to draw the fabric into more intimate contact with the teeth 9 and 12 of the respective parts of the buckle and to hold the buckle more firmly closed, and when the strain is released,

there is no tendency to cause disengagement of the buckle parts.

55

While I have herein shown a single embodiment of my invention, for the purpose of clear disclosure, it will be manifest to persons skilled in the art, that some changes may be made in the general arrangement 60 and configuration of the parts within the scope of the appended claims.

Having described my invention, what I claim is:—

1. A buckle having a frame with a web-threading slot therethrough and forming a pintle bar and a back bar on opposite sides of the slot, a front bar formed integrally with the back bar of the frame and spaced therefrom to form a clamp for one end 70 of a web and having its upper edge notched, and a lever having portions coöoperating with the pintle bar to form a pivot and one edge provided with projections positioned to register with and pass beyond the notches 75 in the front bar when the buckle is closed and acting to deflect the web firmly against the notched edge of the front bar to clamp the web.

2. A buckle comprising a frame formed so into a pintle bar and a back bar in the same plane and a front bar in a different plane, the front bar having a notched edge for engaging a web, and a lever pivoted to the pintle bar and having projections which 85 register with and pass beyond the notched edge of the front bar when the buckle is closed and acting to deflect the web firmly against the notched edge of the front bar and allow the reach of the web to move 90 toward the front of the buckle when the buckle is closed.

3. A buckle comprising a frame slotted to receive a web and form a pintle bar and a back bar in substantially the same plane 95 and having a portion bent to form a front bar in a different plane, and a lever hinged to the pintle bar and having an edge which passes beyond the plane of the pintle and back bars when the buckle is closed to deflect the web tightly against the front bar 100 to hold the web against movement.

In testimony whereof I hereunto subscribe my name.

BENJAMIN F. OREWILER.
